UNITED STATES PATENT OFFICE.

JOHN L. WILCOX, OF FORT HOWARD, WISCONSIN, ASSIGNOR OF ONE-HALF
TO CHARLES EDWARD SHULTZ, OF SAME PLACE.

HARNESS-TUG.

SPECIFICATION forming part of Letters Patent No. 434,648, dated August 19, 1890.

Application filed November 18, 1889. Serial No. 330,783. (No model.)

To all whom it may concern:

Be it known that I, JOHN L. WILCOX, a citizen of the United States, residing at Fort Howard, in the county of Brown and State of Wisconsin, have invented a new Improvement 5 in Harness-Tugs, of which the following is a specification, reference being had to the accompanying drawings, forming a part thereof.

It is known that the ends of heavy harness-tugs are made by doubling the ends of the leather of which the tug is made to form a loop, by which the tug is secured to the hame on one end, and a similar loop for the 15 cockeye on the heel end of the tug to form the loops referred to above requires about twenty-four inches more leather than if the loops were dispensed with. The loops themselves are the only parts of the tug liable to 20 wear out, which are replaced at intervals by splicing, which again requires an unnecessary waste of material and labor.

The object of my improvements is to provide a clasp or clip made of metal or other 25 suitable material, provided with a jaw, which, in combination with a lug to receive a bolt by which it is secured to the hame, forms a hinge-joint. This joint is intended to overcome the rigidity of the material from which 30 the clasp is made, and allows it to adjust itself to any position. The joint is secured by a heavy rivet. The clasp or clip is secured to the leather after it is stitched, and takes the place of the loop referred to above.

Referring to the accompanying drawings, 35 Figure 1 is a side view of my new and improved harness-tug. Fig. 2 is an edge view of the same; and Fig. 3 is a longitudinal central sectional view of the same.

The same letters of reference indicate corresponding parts in all the figures.

Referring to the several parts by letter, the body of my new and improved harness-tug is formed of two parallel plates A A, 45 which are connected at a suitable distance from what may be called their "front ends" by a transverse partition-wall A' integral with

the side plates. Between the front ends of the side plates A is pivotally secured by a pivot-bolt C the flat rounded end of a connecting end piece B. The front end of this pivoted piece B is formed with the two perforated lugs or eyes B' B'. The forward end of the trace D is secured between the side plates A A by means of bolts E, preferably 55 six in number, arranged as shown, while the pivoted end piece B is connected to the hame by means of a pivot-bolt passing through eyes on the outer side of the hame and through the apertured ends B' B' of the piece B. 60

From the foregoing description, taken in connection with the accompanying drawings, the construction, arrangement, and advantages of my invention will be readily understood. 65

It will be seen that my new and improved harness-tug is very simple and strong in construction, and can be manufactured and placed on the market at a moderate cost. The end of the trace is firmly secured between the side plates A A of the device, thus effecting a very considerable saving in leather. The forward ends B of the tugs can be removably secured in a moment to the hames, while by pivoting the end piece B in 70 the main body A, as set forth, a joint is formed in the tug at the point where it is most required, making it easier on the horse, and causing the leather traces to last longer. 75

Having thus described my invention, what I 80 claim, and desire to secure by Letters Patent, is—

In a harness-tug, the combination of the body formed of the two parallel side plates A A, connected near their front ends by the 85 transverse partition-wall A', and the end piece B, having the rounded flat end pivoted between the front end of the plates A and formed with the eyes B' B', substantially as and for the purpose set forth.

JOHN L. WILCOX.
